US00D866350S

(12) **United States Design Patent** (10) **Patent No.:** **US D866,350 S**
(45) **Date of Patent:** **** Nov. 12, 2019**

(54) **WATCH**

(71) Applicants: **Anhui Huami Information Technology Co., Ltd.**, Hefei, Anhui (CN); **Huami Inc.**, Mountain View, CA (US)

(72) Inventors: **Jihyun Park**, Anhui (CN); **Jing Zhao**, Anhui (CN)

(73) Assignees: **Anhui Huami Information Technology Co., Ltd.**, Hefei (CN); **Huami Inc.**, Mountain View, CA (US)

(**) Term: **15 Years**

(21) Appl. No.: **29/616,770**

(22) Filed: **Sep. 8, 2017**

(30) **Foreign Application Priority Data**

May 26, 2017 (CN) 2017 3 0206031

(51) LOC (12) Cl. **10-02**

(52) U.S. Cl.

USPC **D10/38**; D14/344

(58) **Field of Classification Search**

USPC D10/1-3, 14-15, 30-39, 40-41, 98, 102, D10/121-129, 131-132; D11/3-5, 12, D11/18, 19, 23, 93; D14/171, 344

See application file for complete search history.

(57) **CLAIM**

The ornamental design for a watch, as shown and described.

DESCRIPTION

FIG. 1 is a front view of a watch showing our new design. FIG. 2 is a rear view of the watch of FIG. 1.

FIG. 3 is a left side view of the watch of FIG. 1.

FIG. 4 is a right side view of the watch of FIG. 1.

FIG. 5 is a top plan view of the watch of FIG. 1.

FIG. 6 is a bottom plan view of the watch of FIG. 1; and, FIG. 7 is a front, right perspective view the watch of FIG. 1.

The ornamental design which is claimed is shown in solid lines in the drawings. The broken lines in FIGS. 1-7 illustrate environment and form no part of the claimed design. The shade lines in the figures show contour and not surface ornamentation. The shade lines form no part of the claimed design.

1 Claim, 4 Drawing Sheets
